UNITED STATES PATENT OFFICE.

HEINRICH WEGMANN, OF BOCHUM, GERMANY.

SAFETY-LOCK.

1,041,388.

Specification of Letters Patent.

Patented Oct. 15, 1912.

Application filed December 16, 1911. Serial No. 666,113.

To all whom it may concern:

Be it known that I, HEINRICH WEGMANN, a subject of the King of Prussia, of 7 Kronenstrasse, Bochum, in Westphalia, in the Kingdom of Prussia, Empire of Germany, chief machinist, have invented certain new and useful Improvements in Safety-Locks; and I do hereby declare the following to be a full, clear, and exact description of the invention, such as will enable others skilled in the art to which it appertains to make and use the same.

The security hitherto obtained by means of the simpler safety-locks commonly employed on the doors of houses, chambers, cup-boards and the like against professional burglary and theft is principally based upon the shape of key-bits, tubular key-shanks and upon the tumblers coöperating therewith, as it is for instance the case in the so called Chubb-locks, Brahmah-locks and so forth. But even these locks do not in the most cases offer unsurmountable obstacles to skilled burglars and like gentry, so that only the complicated and costly safety-locks usually used on safes and tills must be considered as offering the desired security, but as their first-cost is very high, they cannot come under consideration for common use.

To obviate these drawbacks is the object of my present invention, which is obtained by employing two or more bolts crossing and checking each other in a manner to be moved into or retracted from their several locking-positions in turns during the same rotation of a key having two bits adapted to turn around a common axis in opposite directions until they occupy a given angular position with respect to each other. By means of these simple arrangements it is made possible to obtain perfect security against an unlawful opening of any door etc. provided with this invention, since even in the case, when a key adapted to operate

one of the bolts should be introduced into the lock, the latter could not be opened, since an auxiliary bolt or a group of bolts would still retain their position and prevent the retraction of the first bolt. To still further increase the security thus obtained the key is constructed in such a manner that the two bits or webs can be separated or spread to the desired angle after the key has been inserted into the lock. This peculiarity makes it possible to give the key-hole in the lock-casing, or in the

escutcheon usually secured upon the door, one of the usual shapes, so as not to betray by any visible signs that the lock can only be opened by a key with two bits, or to indicate the angle under which such key-bits have to be arranged one to another.

In the accompanying drawing my invention is explained as applied to a chamber-door mortise-lock, wherein:

Figure 1 is a plan-view of the lock at the beginning of the withdrawal of the dead-bolt, the lock-cover being removed. Fig. 2 is a rear-elevation of the lock. Fig. 3 is a view similar to the one shown in Fig. 1, showing the movable parts at the beginning of the second turn of the main dead-bolt and at the first turn of the auxiliary bolt. Fig. 4 is an elevation of the collapsible or compound key on a larger scale. Fig. 5 is an end-view of the key. Fig. 6 is a sectional view taken on line A—B of Fig. 4, showing the two bits in their opened or working position.

The latch-bolt *a* of the mortise-lock *b* is in the usual manner thrown forward by means of the spring *c* and retracted by the aid of the handle *d*. The nut *e* carries a finger *f* which engages the latch-tail *g* during the retraction of the latch-bolt. Below the latter the main dead-bolt *h* is arranged and guided in the usual manner. In the end-positions this dead-bolt is secured by the tumbler *j* which stands under the influence of the spring *i*. Behind the main dead-bolt the auxiliary dead-bolt or slide *k* is arranged, and guided in the usual manner by means of a slot and pin. In both end-positions this bolt is securely held by means of the tumbler *m* which is continuously acted upon by the spring *l*. When the door has been locked the upper end of the auxiliary dead-bolt *k* takes up a position behind the latch-tail *g*, so that the latch cannot be moved back or forth, and thus besides serving as a latch it also serves as a dead-bolt.

The key-hole *n* shows in the present embodiment of my invention a very simple shape, through which the compound key *o* is pushed with closed bits (Fig. 5) and then opened by means of its two part handle (Fig. 6). This is made possible since the bit *q* forms a part of the tubelike part of the key-shaft, whereas the bit *p* which faces bit *q* is attached to the cylindrical central part of the key-shaft. The bit *p* is thus

adapted to swing within the aperture r of the tubelike part of the key-shaft until both key-bits have been spread sufficiently to form the desired angle.

5 Fig. 1 shows how the longer tooth p' of the bit p has lifted the tumbler j sufficiently to leave the dead-bolt h free and that the latter has been moved a little to the right by means of the shorter middle tooth p'' . A 10 continuation of the rotation of the key causes a further retraction of the dead-bolt h by the aid of the middle tooth p'' and compels the similarly shaped middle tooth q'' of the bit q to enter into the second notch of 15 the dead-bolt h , as indicated in Fig. 3. On continuing the rotation of the key the tooth p''' of the bit p will disengage the tumbler m from the auxiliary dead-bolt k and simultaneously therewith the tooth p' will enter 20 the lower notch of the auxiliary bolt k to draw the latter downward. In the meantime the bolt h has been so far retracted that the bend or curved portion of a slot t with which said bolt is provided is engaged 25 by a pin s of bolt k . Through this curved portion of the slot the pin s will gradually advance toward the vertical part of said slot and enter into it as soon as the middle tooth q'' has fully retracted the dead-bolt h and 30 the tumbler j has locked the latter again, which takes place when the tooth p' leaves the lower notch of the auxiliary dead-bolt k . In the meantime the tooth q'' has engaged the tumbler m and the tooth q' has 35 entered into the upper notch of the auxiliary dead-bolt k , which bolt will have been drawn fully downward when the tooth q' is about to leave the upper notch of the auxiliary bolt k , whereupon the latter will be 40 barred by the tumbler m . All the parts of the lock now take up a position to permit of the door being opened by pressing down one of the handles d .

In order to prevent the main dead-bolt h and the auxiliary dead-bolt k from executing any uncontrollable movements the inner face of the lock-cover is provided with the two leaf-springs u and v , of which the former acts upon the dead-bolt h , as indicated 45 in dotted lines in Fig. 1, and the latter upon the auxiliary bolt k , see Fig. 2.

For locking the door the manipulations described above will naturally succeed each other in the opposite direction.

55 It is evident that for door-locks intended to be locked from within or from without the dimensions of the upper and lower teeth of both key-bits must be alike in shape and

arranged symmetrically to a plane which passes through the middle of the central tooth of both key-bits at right angles to the longitudinal axis of the key. Where this point need not be considered, as for instance in locks intended for drawers, chests, cupboards and the like, differences in the shape 60 and dimensions of the key-bits are not only allowable but may even serve to increase the security obtainable by my lock. I wish it therefore to be understood that all such minor changes may be made within the scope 65 of my present invention.

I claim:

1. A safety lock comprising a bolt having a pair of key-notches, a slide movable at a right angle to the bolt and having a pair of 75 key notches, a latch adapted to be engaged by the slide, and a key having a pair of facing and independently movable bits, one of said bits being adapted to successively engage the first notches of the bolt and slide, 80 while the other bit is adapted to successively engage the second notches of the bolt and slide.

2. A safety lock comprising a bolt, a slide movable at an angle thereto, a latch adapted 85 to be engaged by the slide, a key having a first bit and a second independently movable bit that faces the first bit, the first bit being adapted to start the bolt, the first and second bits being adapted to conjointly complete 90 the movement of the bolt and start the slide while the second bit is adapted to complete the movement of the slide.

3. A safety lock comprising a bolt, a slide movable at an angle thereto, a latch adapted 95 to be engaged by the slide, and a key having a slotted barrel carrying a first bit, and a stem inclosed within said barrel and carrying a second bit that faces the first bit, said first named bit being adapted to engage the 100 bolt, while the second named bit is adapted to successively engage the bolt and slide.

4. A safety lock comprising a bolt having a curved slot, a slide movable at an angle to the bolt and having a pin adapted to engage said slot, a latch adapted to be engaged by the slide, tumblers engaging the bolt and slide, and a key having a pair of facing and independently movable bits that are adapted 105 to operate said bolt and slide.

Signed by me at Barmen, Germany, this 110
4th day of December 1911.

HEINRICH WEGMANN. [L. S.]
